SECURITY DEPOSITORY

Charles F. Meilink, Toledo, Ohio

Application December 18, 1933, Serial No. 702,959

4 Claims. (Cl. 109—1)

This invention relates to protective equipment for receiving valuables and retaining such against unauthorized appropriation.

This invention has utility when incorporated 5 in access interference and control features, especially for safes, as against burglarizing.

Referring to the drawings:

Fig. 1 is a front view of a security depository or safe embodying features of the invention;

10 Fig. 2 is a section on the line II—II, Fig. 1;

Fig. 3 is a fragmentary plan view of the depository top opening of the device of Fig. 1;

15 Fig. 4 is a fragmentary view of features of the lock;

Fig. 5 is a view of the spindle terminus and the knob removed therefrom;

Fig. 6 is a horizontal section looking down into the safe chamber;

20 Fig. 7 is a section on the line VII—VII, Fig. 6;

Fig. 8 is a view of the top receiver of the depository in open or receiving position; and

25 Fig. 9 is a wiring diagram of the control connections.

Cabinet 1 is shown having therein security or 25 valuables receiving chamber 2. This chamber 2 has therefrom top opening 3 provided with metal reinforced throat 4 and ledge 5. At the side of the throat 4 away from the ledge 5 is bar 6 having effective anchorage in the reinforced throat. 30 This bar 6 is a hinge mounting for armored top closure or plate 7 having handle 8.

This closure plate 7, in its lowered position, rests against the upper side of the ledge 5. In lifted position this plate 7 elevates chute therewith. 35 This chute comprises drop portion 9 from the region of the bar 6 and inclined portion 10 between side plates 11 to the plate 7. This portion 10, in extending beyond the side plates 11, has free end 12 abut against the lower side of the 40 ledge 5.

It is thus seen that in lifted position of the plate 7, the portion 10 provides a receiving platform for valuables, and that upon swinging of this plate 7 to its lowered position, the platform 10 then 45 provides an inclined chute to direct the valuables in their passage through the throat 4 and opening 3 into the receiving chamber 2. This access way is so designed that there may be no removal of articles from this chamber 2 by way of the lifted plate 7, for then the portion 10, 12, is an effective 50 interception means.

This safe has additional access thereto by horizontally extending throat 13 to ledge or restriction plate 14 having entrance opening 15, inward 55 from which is ledge 16. In this throat 13, lugs 17

mount hinge bar 18, adjacent one side of the throat as hinge means. Mounted on this bar 18 by brackets 19 is closure plate or door 20 having rigid handle 21 remote from its hinge mounting. This door 20, as swung from the throat toward 5 the chamber 2 to closed position, abuts against the ledge 16. This door 20 on the inner side thereof carries lock box 22 in which is located spindle 23. This spindle 23 extends to have terminus 24 slightly inward from the front of the 10 door 20. This counter-sunk terminus of the spindle 23 is shown as having a pair of eccentric seats 25, 26.

Knob 27 is shown as having graduations 28 to cooperate with pointer 29 in operating tumblers 15 30 of the lock, said tumblers being on the spindle 23. This knob 27 has shoulder 31 to enter the door 20 in the region of the counter-sunk portion of the terminus of the spindle. From this shoulder 31, there extends prong 32 to register with 20 the seat 25 and split prong 33 as a wedge to engage in seat 26. There is thus a frictional anchoring of this knob with the hardened steel spindle. Accordingly, in the event of attack, there may be shattering or removal of this knob 25 27 without injury to the spindle 24.

The tumblers 30 on the spindle 23 may be assembled by manipulation of the knob 27 to bring into alignment a series of notches 34 so that pawl 35 may lower thereinto. This pawl 35 has pivotal 30 mounting 36 on bolt 37 normally slidable in way 38 of the lock box 22. Fixed with this bolt 37 is bolt 39 as the locking bolt proper effective to engage back of the ledge 16 with the door in closed position. The bolt 37 has pin 40, from which extends tension spring 41 to pin 42 fixed with the box 22 and protruding through slot 43 in the bolt 37. It is thus seen that, at a released position of the bolt 37, it is automatically retracted. As the bolt 37 is connected to the pawl 35, the 40 spindle 23, as turned clockwise (Fig. 4) would positively effect withdrawal of locking bolt 39.

As the pawl 35 drops into the notches 34 of the several tumblers of this combination, lock plunger 44 descends and this switch 45, as normally open, 45 is thus closed.

Power supply lines 46 to transformer 47 provide circuit by line 48, to terminal 49, thence by switch member 50, line 51, to the switch 45, thence by line 52, plunger member 50, terminal 49, line 53 50 to relay box 54, coil 62 and line 61. From this box 54 a second circuit extends by line 55 to a terminal 49, plunger 50, by line 56 to coils 57, thence by line 58, a plunger 50, a switch terminal 49, line 59 to the line 48. Time delayed closing of 55

switch disk 60 completes a circuit by line 61 from the transformer 47. This relay 54 has therein winding 62 between the line 55 and the line 61 operable on an escapement, determining the time 5 delay hereunder, for the throwing of the switch 60 to energize the coil 57 to draw armature 57' against the resistance of spring 57'' for the release of the bolt 37.

This device hereunder is so effective that the 10 switch 45 may be reopened during the delayed action of the winding 62, but before such is effective to close the switch 60, there is brought about a re-initiating of this time delay so that its cycle of operation is started over again. It is 15 thus seen that in the manipulation of the spindle 23 a shifting of the pawl 35 out of the notch 34 in the interim wherein there is awaited the chance for the release, there is effective re-cycling of the time, thus bringing about cumulative delay.

20 It is to be noted in this disclosure, transformer 47 and time delay 54 are in auxiliary compartment 63 of the chamber 2, and thereby protected from outside unauthorized interference. The door 20, at open position, precludes any current 25 flow or any operation of the devices of the transformer or relay, in that the door 20 has adjacent its hinge-side lug block 64 carrying insulation sleeve 65 as mountings for the plungers 50, normally urged by springs 66 toward the terminals 30 49 at closed position of the door. At open position of the door, the plungers are swung clear of these terminals.

In opening the door 20, it is to be noted that 35 just inward of this throat, there is inclined way 67 therefrom as a bottom for the chamber 2, thus directing deposit of valuables to repose against rear wall 68. This incline 67 is also effective in receiving the dump from the opening 3 to have 40 such flow also toward the wall 68 as a factor in increasing inaccessibility thereof from the opening 3.

There is produced hereunder a self-contained 45 electric protective installation requiring electric current for release and even at release requiring time delay for any opening to effect removal, although accessible at all times for instantaneous deposit. These cooperative features with cumulative timing against access, due to the recycling feature, materially contribute to the safeguarding 50 of valuables hereunder.

It is to be understood that the operation of the 55 solenoids or coils 57, 62, is not to be sluggish, and accordingly, the winding or voltage is adapted thereto and may be, in instances, for taking line current instead of through a transformer. While four terminals are shown at the block 64, the number thereof may depart therefrom according to the winding control set up selected, to increase or decrease.

60 In the matter of the terminus 24 for the shaft 23, there is sufficient door plate 20 to preclude any attempt to drive this spindle 23 inward from the

front, and accordingly, such is not effective to disturb hardened plate or guard 69. With the door 20 open, should there be rotation of the spindle knob 27, this would allow the dog 57' to swing up into action and thus throw the bolt 5 against closing the door, and there would not be release except with electrical power so to do.

However, this difficulty is overcome by mounting pin 70 to protrude through slot 71 of lock box 22 and housing 72. Accordingly, with the knob 10 27 having been effective to lock the bolt 39 in protruding position, it is only necessary, with the door open, for the one desiring to close the door, to depress the pin 70 so that this bolt 39 may be withdrawn to permit locking of the door. 15

What is claimed and it is desired to secure by Letters Patent is:

1. A safe having a valuables receiving chamber, an opening thereabove, said safe having a double wall housing, an insulation filler between 20 said walls, a reinforced metallic throat for the opening extending between the walls and through said filler, a pivot bearing providing bar anchored inside said throat in proximity to the outer wall, a closure plate for the opening hingedly mounted 25 on the bar, there being ledge means at the throat to limit inward swinging of the closure to closure position, and a chute in the throat fixed to move with the closure and extending downward from the bearing, said chute at lifted position of the 30 closure providing a receiving platform abutting the lower side of the ledge and at lowered position of the closure providing an inclined way into the chamber.

2. A double-walled safe having insulation filler 35 between the walls, a valuables receiving chamber enveloped by said walls, opening means to said chamber provided with metallic throat means, ledge means in the throat means, closure means pivoted at the throat means to swing 40 from outward of the chamber into the throat means against the ledge means to closed position, and inclined way means in the chamber extending from the closed opening means.

3. A repository comprising a housing providing 45 a protective chamber therein, opening means to said chamber, there being chute means from said opening means, closure means for the opening means, said closure means in open position providing a fence against access to the chamber 50 through the opening, and frame means at the opening means anchored with the housing.

4. A double-walled safe having insulation filler 55 between the walls, a valuables receiving chamber enveloped by said walls, an opening through one of said walls provided with a metallic throat through said filler, a ledge in the throat, closure means at the throat to swing from outward of the chamber into the throat against the ledge, 60 and hinge mounting means for the closure.

CHARLES F. MEILINK.
